CENTRALIZED TRAFFIC CONTROLLING
SYSTEM FOR RAILROADS

William D. Hailes, Brighton, N. Y., assignor to
General Railway Signal Company, Rochester,
N. Y.

Application July 30, 1935, Serial No. 33,826

10 Claims. (Cl. 177—353)

This invention relates to centralized traffic controlling system for railroads, and it more particularly pertains to the communication part of such system.

By means of the centralized traffic controlling system contemplated by the present invention a central control office is placed in communication with a number of outlying field stations in such a way that controls may be transmitted to these field stations for governing the operation of traffic controlling devices located at the various stations. Likewise the conditions of the various traffic controlling devices at each station are transmitted from the station to the control office to advise the operator of the location of trains and the condition of the traffic controlling devices, such conditions being transmitted as indications.

The present invention more particularly relates to a centralized traffic controlling system wherein the supervision of the traffic governing devices and the indication of their conditions are accomplished over a communication system comprising two line circuits, namely a control line circuit and an indication line circuit. The present invention is more particularly directed to a traffic controlling system in which the distance between certain of the field stations and the control office is such that it is impractical to transmit impulses between the control office and these certain field stations without the use of undesirably high line voltages or unduly large line conductors, because of the length of the line circuits.

An important feature of the present invention is a storage and repeater arrangement whereby it is possible to operate one or more laterals or branches extending from the main line of the communication system, without the necessity of looping the line circuit of such laterals in series with the main line circuit, with the consequent need of high line voltage and/or large line conductors. It will be obvious from the description which follows that a storage and repeater arrangement as disclosed in the present invention may be installed at the locations where such laterals branch off from the main line, thus repeating controls and/or indications from the main line to these branches with a consequent reduction in line voltage and/or line conductor values required. It will also be obvious that sub-laterals may be branched off the above mentioned laterals by means of the storage and repeater arrangement disclosed, all within the scope of the present invention.

Another object of the present invention is the provision of a repeating circuit arrangement so that distant field stations may operate in connection with the communication system without the need of increasing the size of the line conductors or providing line voltages beyond a reasonable value. As a result of the repeating arrangement provided in the present invention, installation costs of a centralized traffic controlling system are reduced because it is possible to keep the size of the line battery and the line conductors down to a minimum. In other words the present circuit arrangement is so arranged that when the economical limit of line wire size is reached and the economical limit of line battery size is reached, the line circuit will be arranged to repeat into another line circuit and this process can be repeated as often as required. This applies to the control line circuit and the indication line circuit.

Another object of the present invention is the provision of a circuit arrangement for directly repeating impulses from a primary control line circuit which extends from the control office to a repeater location, into a secondary control line circuit which extends from the repeater station to one or more distant field stations.

Another object of the present invention is the provision of a storage arrangement at the repeater location, whereby indications transmitted from a distant field station during one cycle of operation of the communication system are received and stored at the repeater location and then retransmitted from the repeater location to the control office during a succeeding cycle of operations of the communication system.

Still another object of the present invention is the provision of means for precharging the indication line circuit extending from the control office to the repeater location in advance of the transmission of each indication to the control office and for precharging the indication line circuit which extends from the repeater location to the distant field stations in advance of the transmission of each indication to the repeater station.

The advantages of such a precharging arrangement will be briefly pointed out during the following description, while a more detailed discussion of such an arrangement is set forth in applicant's prior Patent No. 2,045,908, granted June 30, 1936.

Other objects, purposes and characteristic features of the present invention will be in part obvious from the accompanying drawings and in

part pointed out as the description of the invention progresses.

In describing the invention in detail reference will be made to the accompanying drawings, in which like reference characters designate corresponding parts, in which distinctive exponents are used at different locations, and in which:—

Figs. 1A and 1B illustrate in a diagrammatic and conventional manner the circuit arrangement at the control office end of the communication system.

Figs. 2A, 2B and 2C illustrate in a diagrammatic and conventional manner the circuit organization at the repeater location.

Fig. 3 illustrates in a diagrammatic and conventional manner the application of the present invention to a field station operating in connection with the communication system.

In following the circuits of the present drawings Fig. 1B should be placed below Fig. 1A, Fig. 2A should be placed to the right of Fig. 1A, Fig. 3 should be placed to the right of Fig. 2A, Fig. 2B should be placed below Fig. 2A and Fig. 2C should be placed below Fig. 2B, with correspondingly identified lines in alignment.

For the purpose of simplifying the illustrations and facilitating in the explanation the various parts and circuits constituting the embodiment of the invention have been shown diagrammatically and certain conventional illustrations have been employed, the drawings having been made more with the purpose of making it easier to understand the processes and mode of operation than with the idea of illustrating the specific construction and arrangement of parts that would be employed in practice. Thus the various relays and their contacts are illustrated in a conventional manner and symbols are used to indicate connections to the terminals of batteries or other sources of electric current instead of showing all of the wiring connections to these terminals.

The symbols (+) and (−) are employed to indicate the positive and negative terminals respectively of suitable batteries or other sources of current and the circuits with which these symbols are used always have current flowing in the same direction, that is from (+) to (−). The symbols (B+) and (B−) are employed to indicate the positive and negative terminals respectively of a battery or other source of direct current having a mid-tap (CN) and the circuits with which these symbols are used may have current flowing in one direction or another depending upon whether the circuit is connected to (B+) or (B−).

In some of the drawings, Figs. 2A, 2B and 2C for example, certain relays have been shown in full lines on one drawing and in dotted lines on an adjacent drawing. The relays shown in dotted lines have been given the same reference characters as applied to these relays shown in full lines since they are the same relays as indicated by the dotted line connections from one drawing to another. It is thus believed unnecessary to show the windings of the relays illustrated in dotted lines since the windings of these relays are indicated in the figures which show the relays by full lines.

Control office equipment.—The control office equipment includes a neutral line relay F which repeats the impulses applied to the control line circuit, comprising control line conductor CL and control return conductor CR, by means of battery CB. Neutral line repeating relay FP re-

peats the impulses applied to relay F and since relay FP is of the quick acting type it follows the operations of relay F with small delay. Neutral line repeating relay 2FP repeats the operations of relay FP. Slow acting relay SA is used for defining the bounds of each operating cycle, this relay being picked up at the beginning of each cycle, remains up throughout the impulses during the cycle and is dropped at the end of the cycle.

Cycle determining relay C and code determining relay CD are picked up at the beginning of a cycle, during which controls are transmitted, by means of starting button SB. The detailed circuits for controlling the operation of relays C and CD are not shown since they are immaterial for an understanding of the present invention and may be arranged as shown in detail in the prior application of T. J. Judge and C. S. Bushnell Ser. No. 640,062 filed Oct. 28, 1932, 20 corresponding to British Patent No. 419,399.

Field cycle determining relay FC remains down during a control cycle but is picked up during a duplex cycle or a cycle for the transmission of indications alone. The circuit arrangement of relay FC is likewise omitted from the present drawing for the sake of simplicity and this relay may have its circuit controlled in the same manner as disclosed in the above mentioned application Ser. No. 640,062.

Code sending relays PC and NC are for the purpose of providing (+) and (−) impulses respectively in the control line circuit during a cycle of operations. Relays MB and MF are for the purpose of receiving indications over the primary indication line circuit, comprising indication line conductor IL and indication return conductor IR, during an operating cycle. The executing circuit arrangement of relays MB and MF is not shown since this arrangement is immaterial for an understanding of the operation of the present embodiment and may be exactly the same as disclosed in the above mentioned prior application No. 640,062. This executing circuit arrangement is controlled by the lower contacts on relays MB, MF, FP and FC as shown in Fig. 1B, with the indication storing relays being omitted. It will be understood that the indication storing relays are selectively energized with (+) or (−) current as determined by the positions of relays MB and MF, with these relays selected by the stepping relay bank as fully disclosed in the above mentioned application Ser. No. 640,062.

A suitable step-by-step relay bank is employed including relays 1V, 1V, 2V and LV. Relays 1V, 2V and LV take their steps during the de-energized or "off" periods of the control line circuit and relay VP shifts its position during the energized or "on" periods of the control line circuit. When the stepping relays are picked up they are stuck up until the end of the cycle. Half-step relay VP is picked up and dropped during alternate "on" periods of the cycle, all of which will be pointed out in detail. Control line 65 impulsive relay E controls the application of impulses to the control line circuit by opening and closing the energizing circuit of the PC and NC relays at the proper times as determined by the response of the stepping relay bank in the control office to the impulses and the time spaces.

Resistance CRS is a charging resistance for charging the indication line circuit extending from the office to the repeater station to apply a flow of charging current at the beginning of

each period of an indication cycle, which follows a period during which the indication line circuit including conductor IL^1 has been conductively closed at the repeater station.

Although not shown in the present drawings it will be understood that the control office is provided with a suitable control machine which includes a miniature track diagram representative of the actual track layout in the field. Certain control levers and buttons which are manually operable to obtain the desired control are included in the control machine, switch machine lever SML and starting button SB being typical of such devices. It will be understood that a starting button is provided for each group of control levers and is associated with a particular field station so that the positioning of the control levers for a particular station results in the transmission of controls to that station following the operation of the associated starting button. Station selection is provided by the particular CD relay which is picked up in response to the operation of a particular starting button, by connecting the PC and NC relays to the channel circuits selected by the stepping relay bank by means of code jumpers connected in various combinations for providing a station selecting code.

Repeater station equipment.—Referring to Figs. 2A, 2B and 2C the repeater station includes a biased to neutral polar line relay F^1 which repeats the polar impulses applied to the primary control line circuit in the control office. The $(+)$ and $(-)$ impulses applied to the primary control line circuit and received by relay F^1 effect the operation of relays PC^1 and NC^1 , respectively, to apply corresponding polar impulses to the secondary control line circuit, comprising control line conductor CL^1 and control return conductor CR^1 extending to the field station or stations beyond the repeater station. These impulses in line CL^1 are repeated (irrespective of their polarity) by neutral relay FN^1 .

A stepping relay bank comprising relays VP^1 , IV^1 , $2V^1$ and LV^1 are operated by the impulses applied to the control line circuit in the office. This stepping relay bank operates substantially in synchronism with the stepping relay bank in the control office, with the exception that relay LV^1 , which responds to the de-energization of control line circuit CL^1 following the last impulse, is not released like the corresponding relay in the control office but remains stuck up and functions as a stored starting relay for initiating a second cycle of operations, following the receipt of a first series of indications transmitted from a distant field station and received in the repeater station.

Relay E^1 responds to the operation of the stepping relay bank and is for the purpose of providing stick circuits for relays MB^1 and MF^1 as will be later pointed out. Relays MB^1 and MF^1 are message receiving relays which correspond to relays MB and MF respectively in the control office. Relays MB^1 and MF^1 receive the indications which are transmitted from a distant field station and cause these indications to be stored by storing relays STO^1 , STO^2 , STO^3 and STO^4 during a particular cycle of operations. These storing relays are energized in various combinations in accordance with the indications received from a distant field station during a particular cycle and are stuck up until the next succeeding cycle, when these indications are transmitted to the control office in accordance

with the combinations of storing relays which were energized during the previous cycle.

Relays FP^1 , $2FP^1$ and SA^1 correspond to relays FP , $2FP$ and SA respectively in the control office, that is relays FP^1 and $2EP^1$ are picked up and dropped in sequence in response to the impulses applied to control line CL . Relay SA^1 is picked up at the beginning of each cycle, remains up throughout the cycle and is dropped at the end of the cycle. Relay SB^1 is a repeater of relay SA^1 .

Relays PB^1 and PF^1 are for the purpose of applying indication impulses to the indication line circuit extending from the repeater station to the control office during a cycle in accordance with the indications which were stored at the repeating station during a preceding cycle as manifested by the particular combination of storing relays picked up.

Relay FC^1 corresponds to relay FC in the control office in that it is picked up in response to the initiation of a cycle from a field station and remains stuck up until the end of the cycle. Lock out relay LO^1 is provided for the purpose of initiating the system in the control office in response to a field start condition at a distant field station and in response to a stored start condition at the repeater station. Relay LO^1 is picked up to initiate an indication cycle and is dropped when such a cycle is initiated from a distant field station. During the consequent cycle the indications are transmitted from the distant field station and stored in the repeater station and at the end of this cycle, relay LO^1 is again picked up to initiate the system through a second cycle of operations and to lock out all distant field stations to prevent any distant field station transmitting indications during this second cycle of operations.

Resistance CRS^1 is a charging resistance for charging the indication line circuit extending from the repeater station to the distant stations to apply a flow of charging current at the beginning of each period of an indication cycle which follows a period during which the indication line circuit including conductor IL^1 has been conductively closed or opened at the field station. Resistance IR^1 is a compensating resistance for compensating for the lower winding of relay LO^1 which is removed from the indication line circuit after the lock-out period of a cycle.

Field station equipment.—Referring to Fig. 3, the field station includes a biased-to-neutral polar line relay F^2 and its repeating relays FP^2 , SA^2 and SB^2 , which operate in a similar manner to corresponding relays in the control office, except that relay F^2 is a polar relay while the corresponding relay in the control office is a neutral relay. Relay SB^2 is a repeater of relay SA^2 .

The field station includes a bank of stepping relays IV^2 , $2V^2$, LV^2 and the associated half-step relay VP^2 operating substantially in synchronism with corresponding relays at the repeater station in response to impulses applied to control line CL^1 and received by relay F^2 . The detailed circuits for operating the stepping relay bank and the line repeater relays are not shown since they may be the same as for corresponding relays in the control office and at the repeater station, with the exception that relay LV^2 is released in the same manner as relay LV in the control office, that is at the end of each cycle. It is thus believed obvious that the line repeater relays and the stepping relays operate in response to the operation of relay FP^2 by means of circuits which are not shown but merely indicated by dotted line connection

Relays PB² and PF² are similar to relays PB¹ and PF¹ at the repeater location. Relays PB² and PF² are controlled locally in accordance with local jumper connections and the positions of local relay contacts. They function to condition the indication line IL¹ in accordance with the indications to be transmitted during the different periods of a cycle as will be pointed out in detail.

Lock out relay LO² is picked up in response to a field start condition at the illustrated station and it functions to energize indication line IL¹ for initiating a cycle of operations for the transmission of indications from the associated station. Relay LO² furthermore locks out distant field stations so that they are ineffective to apply impulses to the indication line circuit during a cycle of operations for the transmission of indications from the illustrated field station.

Resistance 1R² is a compensating resistance for compensating for the resistance of the lower winding of relay LO² which is removed from the indication line circuit after the lock out period. Resistance 2R² is a compensating resistance to compensate for the value of resistance in the indication line circuit which is disconnected when a particular field station is transmitting. When the illustrated field station is transmitting, the indication line IL¹ is connected to the indication return line IR¹ by way of resistance 2R², which resistance is of the proper value to compensate for the resistance of the indication line circuit which would be completed at the end station of a series of field stations connected to the indication line circuit.

Track switch TS is illustrated as being controlled by switch machine SM in response to the operation of switch machine relay SMR. The occupied and unoccupied condition of the illustrated track section is repeated by track relay T in the usual manner.

The control of the signals at the illustrated station has not been shown since the control of the switch machine may be considered typical of the manner in which additional steps of the cycle function to control signals in response to additional impulses. Relay M is the usual signal repeating relay which, when de-energized as shown, indicates that all signals associated with the illustrated track section are at stop and when energized indicates that some signal is clear.

Change relay CH² is normally energized and is dropped (circuits not shown), in response to a changed condition at the associated field station for initiating the system into a cycle of operations for the transmission of indications.

The station selection portion of the system is not illustrated since this feature is immaterial for an understanding of the present invention. Station selection may be provided as explained in detail in the above mentioned application Ser. No. 640,062. It need only be mentioned here that station relay SO² is picked up at the beginning of a control or duplex cycle and remains up throughout the cycle at this station only when controls are to be transmitted to this station.

GENERAL OPERATION

For convenience the control line circuit and the indication line circuit extending from the control office to the repeater station will be referred to as the primary control line circuit and the primary indication line circuit respectively. The control line circuit and the indication line circuit extending from the repeater station to the distant field station will be referred

to as the secondary control line circuit and the secondary indication line circuit respectively. It will be understood that one or more field stations such as shown in Fig. 3 may be interposed in the primary and/or secondary line circuits.

The repeater station of the present invention comprises a stepper and a storage portion. The stepper portion comprises the relays necessary to enable the repeater station to follow the cycles sent out from the control office and to repeat the control line impulses received from the control office. The stepper portion also includes relays necessary to enable the repeater station to respond to the secondary indication line impulses received from distant field stations and also to impulse the primary indication line circuit in order to transmit indications to the control office.

The storage portion of the repeater station includes relays which enable the repeater to store indications received until it has an opportunity to transmit them to the control office. The repeater station has its own control line battery CB¹ and indication line battery IB¹ which furnish the energy for the secondary control and secondary indication line circuits respectively.

In the event that any one of the field stations connected to the secondary line circuit has new indications to transmit to the control office, the transmitting field station first transmits these indications to the repeater station where they are stored. When a set of indications has been stored in the repeater no other indications can be transmitted to the repeater until it has transmitted the stored indications to the control office, which it does on the cycle following the storage cycle, unless some superior field station connected to the primary line circuit takes the line.

If there is a set of indications stored in the repeater station there is also a start condition stored in the repeater station which will remain effective until the repeater station is successful in transmitting its stored indications to the control office.

Indications can be stored in the repeater station or transmitted from the repeater station to the control office by duplex operation, or if the system is not operated for controls a start is initiated automatically for the purpose of transmitting indications originating at a station connected to the secondary line circuit.

The precharging feature for the secondary indication line circuit is provided at the repeater station and functions in the same manner as the precharging feature employed at the control office for the primary indication line circuit.

The stepping and preconditioning of indications and other detailed operations are performed in much the same manner as in an ordinary control office and field station with the exception that: first, when the repeater station is storing indications the stepping at the repeater station follows the line relay of the secondary line circuit, that is relay FN¹, and when the repeater station is transmitting stored indications to the control office the stepping at the repeater station follows the line relay of the primary control line circuit, that is relay F¹. Second, when no indications are being handled by the repeater station, no stepping takes place at the repeater station since only the line relays F¹ and FN¹, the code sending relays PC¹ and NC¹ and the line repeating relays SA¹ and SB¹ operate.

The lock out feature at the repeater station functions the same as at an ordinary field sta-

tion. The repeater station is inferior to all stations connected to the primary line circuits, which are located nearer the control office, and the repeater station is superior to all field stations connected to the secondary line circuits. Thus the lock out feature, superiority, etc., of the field locations connected to the secondary line circuits are the same as for a control office and a series of field stations, the repeater station representing the control office for the group.

One or more repeater stations may be used as required. If more than one repeater station is used the controls are repeated in the same manner as illustrated in the accompanying drawings without any storage feature, while the indications are stored first in the repeater station of the group originating the start condition, then in the next repeater station and finally transmitted to the control office if the repeater stations are used to extend the main circuit. If the repeater stations are used to handle branch lines extending from a main line without repeater stations in the main line, then the repeater stations transmit directly to the control office subject to the geographic superiority, but without the necessity of transferring stored indications to any other repeater station.

The line circuits of a selector system such as disclosed in the above mentioned application Ser. No. 640,062 comprise a control line circuit including control line conductor CL and control return conductor CR and an indication line circuit including indication line conductor IL and indication return conductor IR. These two line circuits correspond to the control line circuit including conductors 10 and 12 and the indication line circuit including conductors 14 and 16 in the above mentioned prior application. In a system of this character the control line conductor CL is connected to the control return conductor CR at the last field station associated with the primary line circuit, with the line relays of any field station or stations between the repeater station and the control office, as well as the line relays at the control office and at the repeater station connected in series with the control line wire.

The primary line circuit is energized with positive and negative impulses from a control line battery in the control office for the purpose of transmitting controls and for the purpose of causing the synchronous step-by-step operation at the control office and at the stations as will be later explained.

The primary indication line circuit is energized from an indication line battery in the control office, having included therein at the control office message receiving relays MF and MB which are controlled through front and back contacts respectively of relays FP and 2FP, as well as through contacts of relays PC and NC. The primary indication line conductor IL extends to all of the field stations connected to the primary line circuits and normally includes a back contact, such as back contact 256 of relay LO² of Fig. 3, at any station located between the office and the repeater station. In the present embodiment the primary indication line conductor terminates at front contact 156 of relay LO¹ at the repeater station.

When a particular field station is transmitting, the lock out relay at the associated station is picked up thereby rendering the open or closed conductive condition of the primary indication line circuit with which the transmit-

ting station is associated, dependent upon the control of either a relay similar to relay PF² or PB² of Fig. 3 in accordance with whether the primary control line circuit is energized or de-energized. It will be understood that the above discussion assumes that one or more field stations are connected to the primary line circuits between the repeater station and the control office.

A similar condition exists with regard to the secondary control and indication line circuits extending from the repeater station to the distant field station or stations, that is the secondary control line circuit includes line relays at these distant stations with the control line conductor CL¹ permanently connected to the return line conductor CR¹ at the end station. The lock out arrangement and the conditioning of the secondary indication line circuit by the PB² and PF² relays associated with the secondary indication line circuit is similar to the functions of corresponding relays associated with the primary indication line circuit, with the secondary indication line circuit normally open ended at the last station.

DETAILED OPERATION

Normal conditions.—With the system in its normal condition as indicated in the accompanying drawings, the primary control line circuit and the secondary control line circuit are both deenergized. The primary indication line circuit and the secondary indication line circuit are both normally held open. All relays in the control office and at the repeater station are normally deenergized. All relays at the field station (Fig. 3) are likewise normally deenergized with the exception of track relay T which is illustrated in its picked up condition, since it is assumed that the associated track section is unoccupied. Change relay CH² is likewise illustrated in its picked up condition since it is assumed that a field start has not been initiated.

For convenience in describing the operations which follow, the energized or impulse periods of the control line circuits will be referred to as "on" periods, while the deenergized or time space periods between impulses will be referred to as "off" periods. The system will be described as stepping through cycles, each comprising a conditioning "on" period, a first "off" period, a first "on" period, a second "off" period, a second "on" period and a third clearing out "off" period.

Manual start.—It will first be assumed that the operator in the control office desires to move track switch TS at the field station, illustrated in Fig. 3, from its normal locked position to its reverse locked position. It will be assumed that the illustrated field station responds to a code combination of (+) and (-) on the first two steps of the communication system. It will also be assumed that the track switch is operated to its reverse position in response to a (-) impulse on the third step of the system.

With the system in its normal condition the actuation of starting button SB in the control office is effective to pick up relays C and CD for initiating a control cycle. Since the detailed circuit arrangement for controlling the C and CD relays is immaterial for an understanding of the present invention it has been omitted from the present disclosure, but this circuit arrangement may be the same as disclosed in the above mentioned application Ser. No. 640,062. It will be understood that only one CD relay can be picked

up at any one time and only at the time the system is in its normal condition.

The picking up of relays CD and C closes a circuit for picking up relay PC which extends a 5 from (+), back contact 40 of relay E, front contact 41 of relay C, back contacts 43 and 44 of relays 2V and 4V respectively, conductor 45, front contact 46 of relay CD, code jumper 5, PC bus 47 and winding of relay PC to (-).

- 10 *Impulsing and stepping operations.*—The picking up of relay PC energizes the primary control line circuit with a (+) impulse to mark the beginning of the conditioning "on" period. This circuit extends from the (+) terminal of battery 15 CB, front contact 51 of relay PC, back contact 54 of relay NC, winding of relay F, primary control line conductor CL, winding of relay F¹, primary control return conductor CR, back contact 58 of relay NC and front contact 53 of relay PC to the 20 (-) terminal of battery CB.

This energization of the primary control line circuit picks up relay F and positions the polar contacts of relay F¹ to the right. Relay F closes an obvious pick-up circuit for relay FP at its 25 front contact 67, relay FP closes an obvious pick-up circuit for relay 2FP at its front contact 68 and relay 2FP closes an obvious pick-up circuit for relay SA at its front contact 69.

Relay F¹ closes an obvious pick-up circuit for 30 relay PC¹ at contact 167 in its right hand dotted position. Relay F¹ closes a pick-up circuit for relay SA¹ which extends from (+), contact 160 of relay F¹ in its right hand dotted position, back contact 161 of relay FC¹, back contact 162 of relay LO¹ and winding of relay SA¹ to (-). Since neither relay FC¹ nor relay LO¹ is picked up during a control cycle, the above described circuit for relay SA¹ is intermittently energized by the intermittent operation of contact 160 of relay F¹ in 35 response to the control impulses applied to the primary control line circuit, which maintains relay SA¹ picked up until the end of the cycle. Relay SA¹ closes an obvious pick-up circuit for relay SB¹ at its front contact 163 which maintains relay SB¹ picked up until the end of the 40 cycle.

The picking up of relay PC¹ energizes the secondary control line circuit with a (+) impulse over a circuit extending from the (+) terminal 45 of battery CB¹, front contact 151 of relay PC¹, back contact 154 of relay NC¹, winding of relay FN¹, control line conductor CL¹, winding of relay F², control return conductor CR¹, back contact 159 of relay NC¹ and front contact 153 of relay PC¹ to the (-) terminal of battery CB¹.

Relay FN¹ is picked up over the secondary control line circuit and relay F² actuates its polar contacts to the right. Since relay FC¹ at the repeater station is not picked up during a control cycle the operation of relay FN¹ during such a cycle is ineffective because of open front contact 164.

At the field station, the actuation of contact 267 of relay F² to the right closes an obvious pick-up circuit for relay FP². Although the detailed circuits are not shown in Fig. 3, in accordance with the operation of the system disclosed in the above mentioned application Ser. No. 640,062, the conditioning (+) impulse applied to the secondary control line effects the pick-up of the station relays at a portion of the field stations, such as relay SO² of Fig. 3. Thus, due to the actuation of contact 214 of relay F² to the right, it will be assumed that relay SO² is 75 picked up and remains in its picked up condition

in response to the station selecting impulses applied to the line circuits for selecting the station illustrated in Fig. 3, so that the first control impulse following station selection will be effective at the illustrated field station due to closed front contact 215 of relay SO².

As above mentioned the detailed circuits for controlling relays SA², SB², VP², 1V², 2V² and LV² at the field station have been omitted, since this control may be effected in the same manner 10 disclosed in the above mentioned application Ser. No. 640,062 and indicated in the present drawing by dotted line 265.

During the impulsing of the primary control line circuit which follows, the stepping relay bank 15 at the repeater station is not operated because of open front contacts 152 and 155 of relays LO¹ and FC¹ respectively.

The energization of the primary and secondary control line circuits as above described is effective 20 to provide the conditioning "on" period of the cycle. During this "on" period relay VP in the control office is picked up over a circuit extending from (+), front contact 71 of relay SA, front contact 72 of relay 2FP, back contacts 85 and 73 of relays 2V and 4V respectively and winding of relay VP to (-). Relay VP closes a first stick circuit for itself extending from (+), front contact 71 of relay SA, front contact 74 of relay VP, back contacts 85 and 73 of relays 2V and 4V 30 respectively and winding of relay VP to (-). The picking up of relay VP closes an energizing circuit for relay E which extends from (+), front contact 90 of relay SA, back contacts 31 and 32 of relays 2V and 4V respectively, front contact 33 of relay VP and winding of relay E to (-).

The picking up of relay E opens the circuit of relay PC at its back contact 40. Relay PC drops and opens the control line circuit to mark the end of the conditioning "on" period and the beginning 40 of the first "off" period. This drops relays F, FP and 2FP in sequence in the control office. Relays F¹ and PC¹ at the repeater station are de-energized in sequence, the dropping of relay PC¹ de-energizing the secondary control line circuit 45 which is effective to drop relays F² and FP² at the field station. Of course relay FN¹ responds to the impulses in the secondary control line circuit but since this relay is ineffective during a control cycle its operation will not be further 50 mentioned during the description of the control cycle operation.

The dropping of relay 2FP in the control office closes a circuit for picking up relay 1V which extends from (+) front contact 75 of relay SA, 55 back contact 76 of relay 2FP, front contact 77 of relay VP, back contact 78 of relay 2V and winding of relay 1V to (-). Relay 1V closes a stick circuit for itself extending from (+), front contact 75 of relay SA, front contact 79 and winding of relay 1V to (-). This stick circuit for relay 1V is maintained energized until relay SA is dropped at the end of the cycle. It will be obvious that relays 2V and LV, when picked up, close similar stick circuits for themselves at their front contacts 83 and 84 respectively and it will not be necessary to point out the closure of these stick circuits again during the operation of the system, since these stick circuits are likewise 70 maintained energized until the end of the cycle.

The picking up of relay 1V opens the first stick circuit of relay VP at back contact 73, but prior to this a second stick circuit is closed for relay VP which extends from (+), front contact 75

71 of relay SA, back contact 72 of relay 2FP, front contact 80 and winding of relay VP to (-).

The picking up of relay 1V de-energizes relay E at back contact 32 and the dropping of relay E picks up relay NC over a circuit extending from 5 (+), back contact 40 of relay E, front contact 41 of relay C, back contact 43 of relay 2V, front contact 44 of relay 1V, conductor 56, front contact 51 of relay CD, jumper 6, NC bus 48 and winding of relay NC to (-).

10 The primary control line circuit is therefore energized with a (-) impulse over a circuit which now extends from battery CB through back contacts 51 and 53 of relay PC and front contacts 50 and 54 of relay NC, which contacts reverse the connection of the battery applied to the primary control line circuit from that previously pointed out.

20 The energization of the primary control line circuit effects the picking up of relays F, FP and 2FP in the control office, positioning of the polar contacts of relay F¹ at the repeater station to the left and the picking up of relay NC¹ over an obvious circuit closed at contact 167 of relay F¹ 25 in its left hand dotted position. With relay NC¹ picked up and relay PC¹ down the secondary control line circuit is energized with a (-) impulse.

30 The picking up of relay 2FP in the control office drops relay VP because the first stick circuit for relay VP is open at back contact 73 of relay 1V and the second stick circuit for relay VP is open at back contact 72 of relay 2FP. The dropping of relay VP closes a circuit for picking up relay E which extends from (+) front contact 35 90 of relay SA, back contact 31 of relay 2V, front contact 32 of relay 1V, back contact 33 of relay VP and winding of relay E to (-).

40 The picking up of relay E de-energizes the above traced circuit for relay NC which drops and de-energizes the primary control line circuit to mark the end of the first "on" period. Relays F, FP and 2FP are dropped in sequence and relay 2V is picked up over a circuit extending from (+), front contact 75 of relay SA, back contact 76 of relay 2FP, back contact 77 of relay VP, front contact 78 of relay 1V and winding of relay 2V to (-). The picking up of relay 2V de-energizes relay E at back contact 31 and the dropping of relay E energizes relay NC which in turn energizes the primary control line circuit to mark the beginning of the second "on" period.

50 Relays F, FP and 2FP are picked up in sequence and relay VP is picked up over a circuit extending from (+), front contact 71 of relay SA, front contact 72 of relay 2FP, front contact 85 of relay 2V and winding of relay VP to (-). Relay VP again completes and prepares its stick circuits which are believed to be obvious and unnecessary to be pointed out again.

60 The picking up of relay VP energizes relay E over a circuit extending from (+), front contact 90 of relay SA, front contacts 31 and 33 of relays 2V and VP respectively and winding of relay E to (-).

65 The picking up of relay E de-energizes relay NC which drops and de-energizes the primary control line circuit to mark the end of the second "on" period and the beginning of the third or releasing out "off" period. Relays F, FP and 2FP are dropped in sequence and relay LV is picked up over a circuit extending from (+), front contact 75 of relay SA, back contact 76 of relay 2FP, front contact 77 of relay VP, front contact 78 of relay 2V and winding of relay LV to (-).

70 The picking up of relay LV does not change the

circuit condition of relay E, therefore this relay remains up, the PC and NC relays remain down and the primary control line circuit remains de-energized so that relay 2FP remains down for a sufficiently long period to drop relay SA and clear out the circuits. The dropping of relay SA de-energizes relays E, VP, 1V, 2V and LV by the opening of its front contacts 90, 71 and 75. The dropping of relay SA also de-energizes relays CD and C, by circuits not shown in the present disclosure.

75 When relay 2V was picked up during the second "off" period as above described, its contact 43 shifted the energizing circuit from conductor 56 to 61, which extends this circuit through front contact 62, lever SML in its right hand dotted line (reverse) position and NC bus 48 to the winding of relay NC. This is effective to make the third impulse applied to the primary control line circuit during the second "on" period (-). 20 It will be understood that lever SML in its left hand (normal) position would energize relay PC instead of relay NC, so that the switch control impulse would be (+) instead of (-).

25 Referring to the field station illustrated in Fig. 3 it will be recalled that the (+) and (-) impulses applied to the primary control line circuit are repeated into the secondary control line circuit by the operation of relays PC¹ and NC¹ respectively at the repeater station. It will be 30 understood that the conditioning and the first impulses which were assumed to be (+) and (-), because of the connections of jumpers 5 and 6 in the control office, were effective to select the station illustrated in Fig. 3 by maintaining relay 35 SO² in its energized condition.

40 After the station is selected the third impulse (second "on"), which was (-) applied to the secondary control line circuit in response to the (-) impulse applied to the primary control line circuit (because lever SML was assumed to be in its reverse position), positions contact 214 of relay F² to the left. This closes a circuit for energizing relay SMR extending from (CN), winding of relay SMR, front contact 216 of relay 2V², front contact 45 215 of relay SO² and contact 214 of relay F² in its left hand dotted position to (B-). This positions contact 250 of relay SMR to its left hand dotted position for controlling the operation of the switch machine for actuating the track switch 50 to its reverse locked position.

55 It will be apparent that a (+) impulse received at the field station during the second "on" period would position contact 214 of relay F² to the right, which would energize relay SMR in the opposite direction for positioning contact 250 to the right for controlling the switch machine to actuate the track switch to its normal locked position.

60 It will be understood that relays F² and FP² which follow the impulses in the secondary control line circuit remain de-energized at the end of the cycle for dropping relays SA², SB², the stepping relays and relay SO². Likewise, relays SA¹ and SB¹ at the repeater station are dropped 65 during the clearing out period because contact 160 of relay F¹ remains in its neutral position for a comparatively long interval of time when the secondary control line circuit is de-energized at the end of the cycle.

70

INDICATIONS

75 *Automatic start.*—Assuming the system to be in its normal condition when a change in condition occurs at a field station, for example the 75

station illustrated in Fig. 3, relay CH² is dropped in response to such a change in condition. This closes a circuit for picking up relay LO² which extends from (+), back contact 207 of relay FP², back contact 238 of relay SB², back contact 253 of relay SA², upper winding of relay LO² and back contact 254 of relay CH² to (-). Relay LO² establishes a substitute circuit to (-) at its front contact 255 which is independent of back contact 254 of relay CH².

The secondary indication line circuit is energized in response to the picking up of relay LO² over a circuit extending from the (+) terminal of battery IB¹ (see Fig. 2C), lower winding of relay MB¹, back contacts 158 and 159 of relays SB¹ and LV¹ respectively, indication line conductor IL¹, front contact 256 of relay LO², back contact 272 of relay SB², lower winding of relay LO², resistance R² and indication return conductor IR¹ to the (-) terminal of battery IB¹.

Relay MB¹ is picked up over the above described circuit and a circuit is closed for picking up relay FC¹ which extends from (+), front contact 165 of relay MB¹, back contact 166 of relay SB¹ and winding of relay FC¹ to (-). The picking up of relay FC¹ closes a circuit for picking up relay LO¹ which extends from (+), back contacts 168, 169 and 170 of relays FP¹, SB¹ and SA¹ respectively, upper winding of relay LO¹ and front contact 171 of relay FC¹ to (-).

The picking up of relay LO¹ closes the primary indication line circuit over a circuit extending from the (+) terminal of battery IB (see Fig. 1B), lower winding of relay MB, back contacts 98 and 97 of relays PC and NC respectively, back contacts 94 and 92 of relays FP and 2FP respectively, front contacts 91 and 81 of relays SA and FC respectively, indication line conductor IL, front contact 156 of relay LO¹, back contact 172 of relay SB¹, back contact 173 of relay FP¹, lower winding of relay LO¹ and indication return conductor IR to the (-) terminal of battery IB.

The closing of the primary indication line circuit picks up relay MB which in turn closes a circuit for picking up relay FC at its front contact 34. The pick-up and stick circuits of relay FC have been omitted from the drawings for the sake of simplicity, since the detailed operation of this relay is immaterial for an understanding of the present invention, it being understood that these circuits can be the same as disclosed in the above-mentioned application Ser. No. 640,062.

Repeater stepping operations.—The picking up of relay FC closes a circuit for picking up relay NC which extends from (+), back contact 40 of relay E, back contact 41 of relay C, front contact 35 of relay FC, NC bus 48 and winding of relay NC to (-). It will be assumed that this is a cycle for the transmission of indications alone (not a duplex cycle), so that relay C remains down and relay FC remains picked up for maintaining relay NC energized throughout the cycle. This provides a series of (-) impulses applied to the primary control line circuit over a circuit extending through front contacts 50 and 54 of relay NC and back contacts 51 and 53 of relay PC.

The energization of relay NC energizes the primary control line circuit with a (-) conditioning impulse which effects the picking up of relays F, FP, 2FP, SA, VP and E in the same manner as previously described.

The picking up of relay E drops relay NC which

de-energizes the primary control line circuit to effect the dropping of relays F, FP, 2FP and the picking of relay IV, which in turn drops relay E for again picking up relay NC which in turn energizes the primary control line circuit with a (-) impulse. 5

It is believed unnecessary to point out in detail how the step-by-step operations in the control office and at the field station (Fig. 3) are effected, since these operations are the same as already described in connection with a control cycle, with the above mentioned exception that the primary control line circuit is energized with a series of (-) impulses. This positions the polar contacts of relay F¹ at the repeater station to 10 the left for each impulse which picks up relay NC¹ to repeat a series of (-) impulses into the secondary control line circuit.

During the step-by-step operations relay FN¹ at the repeater station follows the impulses applied to the secondary control line circuit. Relay MB is dropped when relay 2FP is dropped during the first "off" period of the cycle. The stick circuits for relays MB and MF will be later pointed out. Since the primary indication line circuit is not energized during this first indication cycle relay MB (as well as relay MF) remains down throughout this first cycle.

The conditioning (-) impulse applied to the primary control line circuit energizes the secondary control line circuit with a (-) impulse for picking up relay FN¹. Relay FN¹ closes a circuit for picking up relay FP¹ which extends from (+), front contact 174 of relay FN¹, front contact 164 of relay FC¹ and winding of relay 30 FP¹ to (-). Relay FP¹ closes a circuit for picking up relay 2FP¹ which extends from (+), front contact 175 of relay FC¹, winding of relay 2FP¹ and front contact 176 of relay FP¹ to (-).

The picking up of relay FP¹ opens the primary indication line circuit at back contact 173 and 40 since relays PF¹ and PB¹ are not operated during this first indication cycle the primary indication line circuit remains open throughout the cycle because of open front contacts 177 and 45 178 of relays PF¹ and PB¹ respectively.

The picking up of relay FP¹ opens the local energizing circuit including the upper winding of relay LO¹ at back contact 168 and, since the energizing circuit through the lower winding of relay LO¹ is open at back contact 173 of relay 50 FP¹ and back contact 179 of relay FC¹, relay LO¹ is dropped. This opens the primary indication line circuit at front contact 156, at which point it remains open throughout this first indication cycle. 55

Relay FC¹ is stuck up throughout the first indication cycle over an obvious circuit to (+) at front contacts 147 and 145 in multiple of relays SA¹ and 2FP¹ respectively. Relay MB¹ is 60 dropped during the conditioning "on" period in response to the opening of the secondary indication line circuit by the picking up of relay SB² at the station of Fig. 3. This is because the secondary indication line circuit is opened 65 before relay SB¹ is picked up to close the stick circuit for relay MB¹ at front contact 139.

From the above it will be observed that a change in condition at a field station is effective to operate the system through a cycle during 70 which the primary indication line circuit is not conditioned. It will now be explained how the secondary indication line circuit is conditioned for transmitting indications to the repeater station where they are received and stored, after 75

which a second indication cycle is effected for the transmission of these stored indications to the control office.

The picking up of relay 2FP¹ as above described 5 closes a circuit for picking up relay SA¹ which extends from (+), front contact 168 of relay FP¹, conductor 200, front contact 180 of relay FC¹, front contact 181 of relay 2FP¹ and winding of relay SA¹ to (-). Relay SA¹ closes an obvious pick-up circuit for relay SB¹ at its front contact 163.

Relay VP¹ is now picked up over a circuit extending from (+), front contact 157 of relay SB¹, front contact 155 of relay FC¹, front contact 182 of relay FP¹, back contact 183 of relay 1V¹ and winding of relay VP¹ to (-). Relay VP¹ closes a first stick circuit for itself including the above described circuit and by way of front contact 184 of relay VP¹, which circuit is independent of contacts 155 and 182 of relays FC¹ and FP¹ respectively.

In response to the termination of the conditioning "on" applied to the secondary control line circuit, relays FN¹, FP¹ and 2FP¹ are de- 25 energized in sequence. It will be observed that stepping at the repeater station is controlled by contact 174 of relay FN¹, contact 160 of relay F¹ being ineffective because of open contact 161 of relay FC¹.

30 A circuit is now closed for picking up relay 1V¹ which extends from (+), front contact 157 of relay SB¹, front contact 155 of relay FC¹, back contact 182 of relay FP¹, front contact 185 of relay VP¹, back contact 186 of relay 2V¹ and winding of relay 1V¹ to (-). Relay FP¹ closes a second stick circuit for relay VP¹ to prevent this relay being dropped during the "off" period, which circuit extends from (+) front contact 187 of relay SB¹, back contact 188 of relay FP¹, front contact 189 and winding of relay VP¹ to (-). The picking up of relay 1V¹ closes a stick circuit for itself extending from (+), front contact 157 of relay SB¹, front contact 190 and winding of relay 1V¹ to (-).

45 Relay E¹ is picked up during the conditioning "on" period over a circuit extending from (+), front contact 191 of relay SB¹, front contact 192 of relay FC¹, back contact 193 of relay 2V¹, back contact 194 of relay 1V¹, front contact 195 of relay VP¹ and winding of relay E¹ to (-). In response to the picking up of relay 1V¹ during the first "off" period the above described circuit for relay E¹ is opened at back contact 194 which effects the release of relay E¹.

55 In response to the termination of the first "off" period and the beginning of the first "on" period applied to the secondary control line circuit, relays FN¹, FP¹ and 2FP¹ are picked up in sequence. Relay VP¹ is dropped during this 60 "on" period because its first stick circuit is open at back contact 183 of relay 1V¹ and its second stick circuit is open at back contact 188 of relay FP¹. Relay E¹ is now picked up over the above described circuit which now extends through back contact 195 of relay VP¹ and front contact 194 of relay 1V¹.

65 In response to the termination of the first "on" period and the beginning of the second "off" period relays FN¹, FP¹ and 2FP¹ are dropped in sequence. Relay 2V¹ is picked up over a circuit extending from (+), front contact 157 of relay SB¹, front contact 155 of relay FC¹, back contact 182 of relay FP¹, back contact 185 of relay VP¹, front contact 186 of relay 1V¹ and winding of relay 2V¹ to (-). Relay 2V¹ closes an obvious

stick circuit for itself at its front contact 197. Relay E¹ is dropped during this "off" period because of open back contact 193 of relay 2V¹.

In response to the termination of the second "off" period and the beginning of the second "on" period relays FN¹, FP¹ and 2FP¹ are picked up in sequence. Relay VP¹ is now picked up over a circuit extending from (+), front contact 157 of relay SB¹, front contact 155 of relay FC¹, front contact 182 of relay FP¹, front contact 198 of relay 2V¹ and winding of relay VP¹ to (-). Relay VP¹ closes its first stick circuit at its front contact 184 and prepares its second stick circuit at front contact 189, which circuits are obvious from the previous explanation. Relay E¹ is picked up over the above described pick-up circuit which now includes front contact 193 of relay 2V¹ and front contact 195 of relay VP¹.

In response to the termination of the second "on" period and the beginning of the third "off" period relays FN¹, FP¹ and 2FP¹ are dropped in sequence. A circuit is now closed for picking up relay LV¹ which extends from (+), front contact 157 of relay SB¹, front contact 155 of relay FC¹, back contact 182 of relay FP¹, front contact 185 of relay VP¹, front contact 186 of relay 2V¹ and lower winding of relay LV¹ to (-). Relay LV¹ establishes a stick circuit for itself which extends from (+), back contact 199 of relay LO¹, front contact 149 and upper winding of relay LV¹ to (-). Since relay LO¹ remains down throughout this first cycle and is not picked up until the beginning of the second indication cycle or possibly a later cycle when the repeater station is allowed to transmit, relay LV¹ is maintained stuck up during the clearing out period between cycles by a circuit extending to (+) at back contact 148 of relay 2V¹.

The third "off" period marks the end of the first indication cycle, since there are no further impulses applied to the primary control line circuit in the control office, so that relay 2FP¹ remains down for a period of time sufficient to allow all slow repeater relays to release. Relay SA¹ drops which in turn deenergizes relay SB¹ at open front contact 163 and the dropping of relay SB¹ deenergizes relays VP¹, 1V¹ and 2V¹ at open front contacts 157 and 187. Relay SA¹ deenergizes relay FC¹ at open front contact 147. The opening of front contact 192 of relay FC¹ de- 50 energizes relay E¹.

Transmission of indications to repeater station.—During the operation of the first indication cycle above described, indications are transmitted from the field station illustrated in Fig. 3 to the repeater station illustrated in Figs. 2A, 2B and 2C by the conditioning of the secondary indication line circuit. Relays LO² and SB² remain picked up at the field station throughout this first indication cycle so that the circuit of the secondary indication line including front contact 272 of relay SB², can be energized or de-energized during both the "on" and "off" periods as selected by contact 273 of relay FP² in accordance with the closed or open conditions of contacts 299 and 291 of relays PF² and PB² respectively. 60

65 During each "off" period in the series of impulses the (+) terminal of indication battery IB¹ (Fig. 2C) is connected to secondary indication line conductor IL¹ through the lower winding of relay MB¹ and current flow in the secondary indication line circuit is dependent upon front contact 291 of relay PB². More specifically, relay PB² is the code transmitter for the "off" periods 70 75

of the series. Assuming jumper 280 at the field station to be connected to (+) as shown, relay PB² is picked up during the conditioning "on" period over a circuit extending from (+), jumper 280, back contacts 285 and 286 of relays 1V² and 2V² respectively, front contact 288 of relay FP², winding of relay PB² and front contact 289 of relay LO² to (-). The picking up of relay PB² provides one of a choice of two "off" indication 10 codes.

When relay FP² is dropped during the first "off" period relay PB² is stuck up over a circuit extending from (+), front contact 290 of relay PB², back contact 288 of relay FP², winding of relay 15 PB² and front contact 289 of relay LO² to (-). When relay FP² is picked up during the first "on" period the above described stick circuit is opened and the energization of relay PB² is dependent upon a circuit extending through front contact 20 285 of relay 1V² for the second "off" indication, to contact 292 of relay T, which being open illustrates the alternate choice of an "off" indication. Relay PB² will be deenergized.

During the second "on" period the energization 25 of relay PB² is dependent upon the energization of a circuit including front contact 286 of relay 2V², which circuit has not been shown because the above examples are typical of the choice of two conditions for the transmission of 30 "off" indications.

With relay PB² picked up during the conditioning "on" period and stuck up throughout the first "off" period as above described, the secondary indication line circuit is closed as will be presently 35 pointed out. This indication line circuit was opened during the conditioning "on" period when relay SB² opened its back contact 272.

The lock out period for maintaining relay LO² energized extends from the time of the picking up 40 of relay FP² and the consequent opening of its back contact 207 until the picking up of relay SA² and the consequent closing of its front contact 253, during which period relay LO² is dependent 45 for its energization on line current received from battery IB¹ at the repeater station and through its lower winding. In the event that some other station superior to the station of Fig. 3 opens the secondary indication line circuit during this lock out period, then of course relay LO² is 50 dropped during the lock out period and it cannot be picked up again until the start of another cycle. With relay LO² maintained picked up during the lock out period, then when relay SA² closes its front contact 253, relay LO² is stuck up over a 55 circuit including its upper winding and its front contacts 255 and 268 in series with front contact 253 of relay SA². Thus relay LO² is maintained picked up until relay SA² drops at the end of the cycle.

60 During each "on" period the secondary indication line circuit remains open or is closed depending upon contact 299 of relay PF². For example, assuming that code jumper 282 is connected to (+) as shown in Fig. 3, then relay PF² 65 is picked up during the first "off" period over a circuit extending from (+), jumper 282, back contact 294 of relay 2V², front contact 296 of relay VP², back contact 297 of relay FP², winding of relay PF² and front contact 289 of relay LO² to 70 (-). When relay FP² is picked up during the first "on" period relay PF² is stuck up over a circuit extending from (+), front contact 298 of relay PF², front contact 297 of relay FP², winding of relay PF² and front contact 289 of relay LO² to 75 (-). The above illustrates one choice of an "on"

indication whereby relay PF² is picked up. The other choice of an "on" indication is effected by the deenergization of the circuit including the winding of relay PF² and back contact 207 of relay FP². The first choice "on" indication again energizes relay PF² in the second "off" period, while the other choice "on" indication does not effect the picking up of relay PF² during an "off" period so that it is down throughout the following "on" period.

10 Since relay M is assumed to be deenergized and its back contact 201 closed, the second "on" indication is the same as the first "on" indication because relay PF² will be picked up during the second "off" period over a circuit extending through back contact 201 of relay M, front contact 293 of relay 1V², back contact 286 of relay VP² and back contact 297 of relay FP² to the winding of relay PF². The third "on" indication is selected through front contact 294 of relay 2V², 20 which circuit is not shown since it is believed the above examples are sufficient to illustrate the choice of two "on" indications which may be provided at each step of the system.

It will now be explained how the conditioning 25 of relays PB² and PF² effects the closing and the opening of the secondary indication line circuit for transmitting indications to the repeater station where they are received and stored.

From the above discussion of the conditioning 30 of the PB² and PF² relays it will be observed that relay PF² is positioned during an "off" period in accordance with the indication it is to transmit in the next "on" period, while relay PB² is positioned during an "on" period in accordance with the indication it is to transmit in the next "off" period. Thus on each step taken by the step-by-step mechanism at the field station relays PF² and 35 PB² govern the secondary indication line circuit.

It will be recalled that the secondary indication line circuit was opened during the conditioning "on" period by the picking up of relay SB² and the consequent opening of its back contact 272. The dropping of relay 2FP¹ at the repeater station during the first "off" period permits current to flow in the secondary indication line circuit (because relay PB² is picked up 45 throughout this "off" period), over a circuit extending from the (+) terminal of battery IB¹ at the repeater station, lower winding of relay 50 MB¹, back contacts 144 and 143 of relays PC¹ and NC¹ respectively, back contact 142 of relay FP¹, back contact 141 of relay 2FP¹, front contact 149 of relay SA¹, front contact 153 of relay SB¹, back contact 159 of relay LV¹, secondary 55 indication line conductor IL¹, front contacts 256 and 272 of relays LO² and SB² respectively, back contact 273 of relay FP², front contact 291 of relay PB², resistance 2R² and indication return conductor IR¹ to the (-) terminal of battery 60 IB¹.

This energization of the secondary indication line circuit picks up relay MB¹ and it is stuck up over a circuit extending from (+), front contact 130 of relay SB¹, back contact 133 of 65 relay E¹, front contact 134 and upper winding of relay MB¹ to (-). During the first "on" period the picking up of relay 2FP¹ (before the picking up of relay E¹) closes a substitute stick circuit for relay MB¹ which extends through front contact 130 of relay SB¹ and front contact 131 of relay 70 2FP¹. Relay MB¹ is thus stuck up when picked up throughout the "on" period following the "off" period during which it was picked up.

The picking up of relay NC¹ at the repeater 75

station to mark the beginning of the first "on" period opens the secondary indication line circuit at back contact 143. This deenergizes the secondary indication line circuit and when relay 5 2FP¹ is picked up during the first "on" period the secondary indication line circuit is again energized because relay PF² at the field station is up.

The energizing circuit for the secondary indication line circuit extends from the (+) terminal 10 of battery IB¹, lower winding of relay MF¹, back contact 135 of relay PC¹, front contact 136 of relay NC¹, front contact 137 of relay FP¹, front contact 141 of relay 2FP¹, front contact 140 of relay SA¹, front contact 158 of relay SB¹, back contact 159 of relay LV¹, indication line conductor IL¹, front contacts 256 and 272 of relays LO² 15 and SB² respectively, front contacts 273 and 299 of relays FP² and PF² respectively, resistance 2R² 20 and indication return conductor IR¹ to the (-) terminal of battery IB¹. This effects the energization of relay MF¹ and since relay E¹ is picked up during this first "on" period, relay MF¹ is stuck up over a circuit extending from (+), front contacts 130 and 133 of relays SB¹ and E¹ respectively, front contact 138 and winding of relay 25 MF¹ to (-).

When relay 2FP¹ is dropped during the succeeding (second) "off" period relay MF¹ is stuck up over a circuit including back contact 131 of relay 2FP¹. It will thus be observed that relay MF¹ when picked up during an "on" period is stuck up throughout the following "off" period. The dropping of relay 2FP¹ during the second 35 "off" period fails to close the secondary indication line circuit because of open front contact 291 of relay PB².

When relay 2FP¹ is picked up during the second "on" period then the secondary indication line 40 circuit is closed because relay PF² is picked up throughout this period. It is believed unnecessary to trace the energizing circuit for the secondary indication line since it is the same as previously traced.

Since the secondary indication line circuit is not energized during the second "off" period in response to the dropping of relay 2FP¹, relay MB¹ is dropped during this period when relay 2FP¹ 45 opens its front contact 131 because the stick circuit for relay MB¹ is de-energized at open back contact 133 of relay E¹ and open front contact 131 of relay 2FP¹.

The energization of the secondary indication line circuit during the second "on" period picks up relay MF¹ as previously described and this relay is stuck up for a sufficient period of time 50 during the following "off" period to execute this particular indication condition. In the event that relay PF² is down throughout the second "on" period the relay MF¹ is dropped when relay 2FP¹ 55 opens its back contact 131 to de-energize the stick circuit of relay MF¹ before it is energized by the closure of front contact 133 of relay E¹.

During the last "off" (clearing out) period the 60 secondary indication line circuit is de-energized by the dropping of relay NC¹ and the opening of its front contact 136. Relay MF¹, which was stuck up throughout the second "on" period, is dropped in the clearing out period when relay 65 SB¹ drops and opens its front contact 130. Relay PF², which was stuck up throughout the second "on" period, is dropped when relay FP² drops and opens its front contact 297 in the clearing out period.

75 From the above it will be observed that relay

MB¹ is selectively responsive during the "off" periods to the energization and de-energization of the secondary indication line circuit for receiving either one of a choice of two distinctive indications, with the selected choice maintained throughout the following "on" period by relay MB¹ either being up or down throughout this "on" period. Furthermore, relay MF¹ is selectively responsive during each "on" period in accordance with one or another choice of two indications transmitted during each "on" period, with relay MF¹ remaining up or down throughout the following "off" period to register the selected indication which was transmitted and received by this relay.

Storage of indications.—Storage relays STO¹ and STO³ store the "off" indications received by relay MB¹ and storage relays STO² and STO⁴ store the "on" indications received by relay MF¹. It will be understood that additional storage relays may be provided when additional steps are used at the repeater station.

It will be recalled that relay MB¹ was maintained in its picked up position throughout the first "on" period in accordance with the indication received in the previous "off" period. With relay MB¹ picked up a circuit is closed during the first "on" period for energizing relay STO¹ which extends from (+), front contacts 120 and 121 of relays MB¹ and FP¹ respectively, front contact 122 of relay FC¹, back contact 123 of relay 2V¹, front contact 124 of relay IV¹ and winding of relay STO¹ to (-). Relay STO¹ closes a stick circuit for itself extending from (+), front contact 139 of relay SB¹, front contact 125 and winding of relay STO¹ to (-). Since relay MB¹ is not up during the second "on" period relay STO³ is not picked up.

It will be recalled that relay MF¹ is up throughout the second "off" period, which is effective to 40 close a pick-up circuit for relay STO² which extends from (+), front contact 126 of relay MF¹, back contact 127 of relay FP¹, front contact 128 of relay FC¹, back contact 129 of relay VP¹, front contact 110 of relay IV¹ and winding of relay 45 STO² to (-). Relay STO² closes an obvious stick circuit for itself at its front contact 111.

Since relay MF¹ is up during the third "off" period following the dropping of relay FP¹, a pick-up circuit is closed for relay STO⁴ similar to the 50 above described circuit for STO², but extending through front contacts 112 and 129 of relays 2V¹ and VP¹ respectively. Relay STO⁴ closes an obvious stick circuit for itself at its front contact 113. From the above discussion of the operation 55 of the storage relays it will be apparent that the choice of each "off" indication effects the energization or the de-energization of relays STO¹ and STO³, while the choice of the "on" indications effects the energization or the de-energization of relays STO² and STO⁴.

Repeating the stored indications.—Recalling that relay LV¹ at the repeater station was picked up during the third "off" period and was not dropped when relays SA¹ and SB¹ were dropped 65 to de-energize the other relays which were stuck up throughout this cycle, it will be obvious that the storage relays which were picked up are maintained stuck up because of closed front contact 114 of relay LV¹.

The dropping of relay VP¹ at the repeater station during the clearing out period closes an energizing circuit for relay LO¹ which extends from (+), back contacts 168, 169 and 170 of relays FP¹, SB¹ and SA¹ respectively, upper wind- 75

ing of relay LO¹, back contact 171 of relay FC¹, front contact 115 of relay LV¹ and back contact 116 of relay VP¹ to (-). Relay LO¹ establishes a stick circuit for itself by way of its front contact 117 which is effective after the picking up of relay VP¹. At its front contact 118 a stick circuit is established through back contact 119 of relay FC¹ and front contact 170 of relay SA¹, which is effective after the lock out period.

- 10 In the event that there are one or more field stations connected to the primary line circuits between the repeater station and the control office, then the lock out arrangement at these field stations is effective to prevent the transmission of repeater station stored indications to the control office, in the event that indications are ready for transmission at some one of these superior field locations. The lock out feature at the repeater station is effective to drop relay LO¹ 15 in the event that the primary indication line circuit is interrupted by a superior field station. This feature is effective during the time interval between the picking up of relay FP¹ and the consequent de-energization of the upper winding of relay LO¹ at back contact 168 and the re-energization of this upper winding by the picking up 20 of relay SA¹ and the consequent closure of its front contact 170. It will be obvious that during this interval, if the primary indication line circuit 25 is open at some superior station, then relay LO¹ cannot be maintained energized and it will be dropped away before relay SA¹ is picked up to complete its permanent stick circuit at contact 170.

- 30 The picking up of relay LO¹ previously described closes the primary indication line circuit by the closure of front contact 156 over the circuit which was previously pointed out. Following this energization of the primary indication line circuit relays MB, FC and NC in the control office are picked up as previously described, with the picking up of relay NC energizing the primary control line circuit to start the system through a second cycle of operations. The primary control line circuit is impulsed with a series of (-) impulses throughout this second indication cycle and relays F, FP, 2FP, SA, E, NC and the stepping relay bank all operate in the manner previously described. Relay MB is stuck up until relay 2FP drops in the first "off" period 40 to connect the lower winding of relay MB in the primary indication line circuit as later described. This stick circuit extends from (+), front contact 60 of relay SA, front contact 64 of relay 2FP, front contact 65 and winding of relay MB 45 to (-).

- 50 Since it is assumed that no controls are to be transmitted during this second indication cycle, a series of (-) impulses are applied to the primary control line circuit. Relay NC¹ at the repeater station follows these impulses to transmit a series of (-) impulses over the secondary control line circuit. These (-) impulses applied to the secondary control line circuit effect the intermittent operation of relays F¹ and FN¹ as before but, because relay FC¹ is not picked up during this second indication cycle, the operation of relay FN¹ is not effective to control the line repeater relays because of open front contact 164. The intermittent actuation of contact 160 of relay F¹ is effective to control the line repeater relays at the repeater station because of closed back contact 161 of relay FC¹.

55 The line relays at the field stations, such as the station illustrated in Fig. 3, are responsive

to the impulses applied to the secondary control line circuit during this second indication cycle but, in accordance with the operation of the system disclosed in the above mentioned application Ser. No. 640,062, stepping does not take place at these stations because neither the station selecting relays (such as relay SO²) nor the lock out relays (such as relay LO²) are picked up.

60 The first or conditioning impulse applied to the control line circuit actuates contact 160 of relay F¹ to the left which closes a circuit for picking up relay FP¹ extending from (+), contact 160 in its right hand dotted position, back contact 161 of relay FC¹, back contact 109 of relay SB¹ and winding of relay FP¹ to (-). A circuit in multiple with contact 109 extends through front contact 162 of relay LO¹. A circuit is closed for picking up relay SA¹ which extends from (+), front contact 163 of relay FP¹, conductor 200, back contact 160 of relay FC¹ and winding of relay SA¹ to (-). Relay 2FP¹ is not picked up during this cycle because of open front contact 175 of relay FC¹, but relay SB¹ is picked up over an obvious circuit including front contact 163 of relay SA¹.

65 The intermittent operation of relay FP¹ during this second indication cycle is effective to operate the stepping relay bank as previously described because of closed front contact 152 of relay LO¹. The system therefore steps through a cycle of 30 operations in the manner previously described.

70 During this second cycle of operations, relays PB¹ and PF¹ at the repeater station are positioned in accordance with the positions of the storage relays and the primary indication line circuit is impulsed in accordance with the positions of relays PB¹ and PF¹ in much the same manner as described in connection with the impulsing of the secondary indication line circuit in accordance with the positions of relays PB² and PF².

75 For example, with relay STO¹ picked up and stuck up as previously explained relay PB¹ is picked up when relay FP¹ picks up, by means of a circuit extending from (+), front contact 100 of relay STO¹, back contacts 101 and 102 of relays 45 1V¹ and 2V¹ respectively, front contact 103 of relay FP¹, winding of relay PB¹ and front contact 104 of relay LO¹ to (-). When relay FP¹ is dropped at the end of the conditioning "on" period 50 relay PB¹ is stuck up over an obvious circuit including its front contact 105. This stick circuit is maintained throughout the first "off" period so that relay PB¹ when picked up is stuck up until relay FP¹ again picks up to open its back 55 contact 103.

60 The closure of front contact 103 extends the circuit of relay PB¹ by way of back contact 102 of relay 2V¹ and front contact 101 of relay 1V¹ to front contact 106 of relay STO³, but since relay STO³ is not picked up relay PB¹ will not be energized at this time. It drops because both its pick-up and stick circuits are open. When relay PB¹ is not picked up during an "on" period it remains down throughout the following "off" 65 period. The above illustrates how the "off" indications stored by relays STO¹ and STO³ are effective to position relay PB¹.

65 Recalling that relay STO² was picked up and stuck up, the dropping of relay FP¹ at the beginning of the first "off" period closes a circuit for picking up relay FP¹ which extends from (+), front contact 107 of relay STO², back contact 108 of relay 70 2V¹, front contact 220 of relay VP¹, back contact 221 of relay FP¹, winding of relay PF¹ and 75

front contact 104 of relay LO¹ to (-). With relay PF¹ picked up it is stuck up when relay FP¹ picks up at the end of the first "off" period over an obvious circuit including front contact 221 of relay FP¹ and front contact 222 of relay PF¹.

The dropping of relay FP¹ at the end of the first "on" period de-energizes the above described stick circuit for relay PF¹, but since relay STO⁴ is picked up relay PF¹ is immediately energized over a circuit extending from (+), front contact 223 of relay STO⁴, front contact 224 of relay LV¹, back contact 220 of relay VP¹, back contact 221 of relay FP¹, winding of relay PF¹ and front contact 104 of relay LO¹ to (-). Relay PF¹ is again stuck up when relay FP¹ is picked up at the beginning of the second "on" period. The above illustrates how relay PF¹ is picked up during an "off" period and maintained picked up throughout the following "on" period for one choice indication. It is believed obvious that the other choice indication is effected by relays STO² or STO⁴ being down to effect the de-energization of relay PF¹ when relay FP¹ is dropped so that relay PF¹ will be down throughout the following "on" period.

Relay PB¹ is picked up during the conditioning "on" period in preparation for the first "off" indication as one which shall close the primary indication line circuit, but this line circuit is not closed by PB¹ until the following "off" period. When relays NC, FP and 2FP are dropped in the control office to apply energy to the primary indication line circuit by way of back contacts 97, 94 and 92 respectively, the primary indication line circuit is completed because of closed front contact 178 of relay PB¹ at the repeater station.

When relay NC in the control office picks up and opens its back contact 97 at the beginning of the first "on" period, the primary indication line is de-energized and the circuit including the primary indication line is switched from relay MB to relay MF by way of front contacts 93 and 92 of relays FP and 2FP respectively, when these relays are picked up during the first "on" period. Since relay PF¹ is up for the transmission of an impulse over the primary indication line circuit during the first "on" period, the closure of front contact 225 of relay FP¹ completes the energizing circuit for the primary indication line circuit by way of front contact 177 of relay PF¹. Then when relay NC drops and opens its front contact 95 at the beginning of the second "off" period the primary indication line circuit is de-energized.

Since relay PB¹ is left down in preparation for a non-pulse of the primary indication line circuit for the second "off" period, the dropping of relays FP and 2FP in the control office are ineffective to close the primary indication line circuit with back contact 97 of relay NC closed because of open front contact 178 of relay PB¹.

Since relay PF¹ is up in preparation for a pulse for the second "on" indication of the primary indication line circuit the picking up of relays NC, FP and 2FP in the control office completes the primary indication line circuit because of closed front contact 177 of relay PF¹.

From the above it will be observed how the primary indication line circuit is pulsed or not pulsed to provide a choice of two "off" indications in accordance with the position of relay PB¹ at each step and how this indication line circuit is pulsed or not pulsed to provide a choice of two "on" indications in accordance with the position of relay PF¹ at each step.

This conditioning of the primary indication line

circuit effects the energization and the de-energization of the MB and MF relays in the control office in exactly the same manner as described in connection with the impulsing of the secondary indication line circuit for energizing and de-energizing relays MB¹ and MF¹ at the repeater station. Furthermore, this conditioning of the primary indication line circuit transmits codes to the control office where they are received by the MB and MF relays and stored on indication receiving relays in the same manner as described in the above mentioned application Ser. No. 640,062. It is therefore believed unnecessary to point out in detail how the positioning of the MB and MF relays in the office is effective to transfer the received codes to indication storing relays.

It will be pointed out however how the MB and MF relays, when picked up in the "off" and "on" periods respectively, are stuck up throughout the following "on" and "off" periods respectively.

When relay MB is picked up during the first "off" period as above described, a stick circuit is closed for this relay which extends from (+), front contact 60 of relay SA, back contact 63 of relay E (relay E being dropped before the indication line circuit is de-energized), front contact 65 and upper winding of relay MB to (-). Since relay 2FP is picked up during the first "on" period before relay E is picked up, a substitute stick circuit is closed by way of front contact 64 of relay 2FP which is effective to maintain relay MB stuck up until the following "off" period, when its energization is determined by the closed condition of the primary indication line circuit for the second "off" indication.

With relay MF picked up in the first "on" period as above described, a stick circuit is closed for this relay which extends from (+), front contact 60 of relay SA, front contact 63 of relay E, front contact 66 and upper winding of relay MF to (-). This circuit is completed through front contact 63 of relay E because relay E is picked up before the primary indication line circuit is opened to de-energize the lower winding of relay MF. Since relay 2FP is dropped before relay E opens its front contact 63, a substitute stick circuit is closed for relay MF which extends through back contact 64 of relay 2FP. When relay 2FP picks up during the second "on" period the stick circuit of relay MF is de-energized and relay MF is dependent upon the energization of the primary indication line circuit for the energization of its lower winding.

It is believed that the above examples relating to the stick circuits for the MB and MF relays when picked up during the first "off" and first "on" periods respectively are sufficient to indicate how these relays are stuck up when picked up during other "off" and "on" periods.

At the end of the second indication cycle, during which the stored indications are transmitted to the control office, the last "off" period of the control line circuits is effective to de-energize the SA and SB relays in the control office and at the repeater station in the same manner as previously described. The stepping relays are de-energized as previously described and the storage relays at the repeater station are de-energized when relay SB drops and opens its front contact 139, since at this time relay LV¹ will have been dropped to open its front contact 114. Relay LV¹ is de-energized during the second "on" period by the opening of back contact 226 of relay VP¹. It will be obvious that back contact 148 of 75

relay $2V^1$ is open at this time and therefore the stick circuit of relay LV^1 is de-energized.

Indication line circuit precharging.—From the foregoing description it will be observed that the indication receiving relays MF^1 and MB^1 at the repeater station and the indication receiving relays MF and MB in the control office are connected in the secondary indication line circuit and the primary indication line circuit respectively, 5 in such a manner that they are controlled in accordance with the open or closed condition of transmitting contacts at the outlying field station and at the repeater station respectively. With this arrangement it happens that the sequence of 10 events is such that the distributed capacity of the indication line circuits may become discharged so that the application of energy to these circuits may result in a temporary surge of current which is conveniently termed the charging current. 15 This charging current flows irrespective of whether the line circuit is open or closed at the location from which an indication is to be received.

It has been found in some instances that the 20 charging current that flows into an open circuited indication line reaches a peak value which is considerably greater than the current that normally flows under the stable conductive condition of the line circuit and that this charging current surge lasts for an appreciable length of time. Under these conditions the message receiving relay in the indication line circuit, for the purpose of detecting the conductive condition of the line, 25 may be undesirably picked up by the charging current when such relay was supposed to remain down in accordance with the open circuit condition of the line.

It will be recalled that the primary indication line circuit was not impulsed during the first 30 indication cycle above described because of open front contact 156 of relay LO^1 of Fig. 2C. During this cycle the contact arrangement comprising contacts 92 , 93 and 94 of relays $2FP$ and FP of Fig. 1B apply a charge to the primary indication line circuit at each period of the cycle, which is effective to prevent the false energization of relay MB or MF due to the capacity of the primary indication line circuit. Of course the primary indication line circuit is maintained open throughout 35 out this first cycle so that one charge would be sufficient. However during the second cycle a repeated charge is required because the primary indication line circuit may be repeatedly discharged by a closed contact at a field location. 40 During the first indication cycle however, the secondary indication line circuit connecting the repeater station with the distant field station is impulsed and the contact arrangement, comprising contacts 141 , 137 and 142 of relays $2FP^1$ and FP^1 of Fig. 2C, is effective to precharge the secondary indication line circuit.

During the transfer from one period to another, that is from an "on" period to an "off" period or vice versa, there is an interval of time during 45 which the secondary indication line circuit is not energized from indication battery IB^1 and during which time the distributed capacity of the secondary indication line circuit may become discharged by reason of the closed condition of one 50 of its controlling contacts at the field station. This is because the field station apparatus is not permitted to change the condition of the secondary indication line circuit until after this line circuit is opened at the repeater station, which 55 is necessary to provide that the message receiv-

ing relays MF^1 and MB^1 will be properly controlled. Thereafter, the transfer at the field station occurs so that upon the closure of the secondary indication line circuit at the repeater station, the conductive circuit then established is 10 dependent upon the governing contact at the field station. Thus it is obvious that a charging current will flow at the beginning of each period which follows a period during which the secondary indication line circuit has been conductively closed at the field station, or at the beginning of 15 a period following an interval during which the line may have been discharged for any other reason. The same discussion applies to the operation of relays MF and MB in the office, with 20 energy applied to the primary indication line circuit from battery IB .

During an "on" period for example, relays FP^1 and $2FP^1$ at the repeater station are picked up. The relay MF^1 is energized or not depending upon 25 the closed or open condition of contact 299 of relay PF^2 at the field station. It will be assumed that contact 299 of relay PF^2 is closed during the first "on" period. Therefore relay MF^1 will be picked up, but just before it is connected into the secondary indication line circuit this line circuit is precharged.

When relay NC^1 picks up to mark the beginning of the first "on" period in the control line circuit, the indication battery IB^1 is disconnected 30 from the secondary indication line at the same instant by the opening of front contact 143 of relay NC^1 . During the interval between the picking up of relay FP^1 and the picking up of relay $2FP^1$, the indication battery is connected 35 to the secondary indication line circuit through charging resistor CRS^1 over a circuit extending from the (+) terminal of battery IB^1 , resistor CRS^1 , front contact 142 of relay FP^1 , back contact 141 of relay $2FP^1$, front contact 140 of relay 40 SA^1 , front contact 153 of relay SB^1 and back contact 159 of relay LV^1 to secondary indication line conductor IL^1 . This connection of battery IB^1 to the secondary indication line circuit through resistor CRS^1 is effective to apply a 45 charging current to the secondary indication line circuit before the winding of relay MF^1 is inserted in this line circuit to detect its closed or open condition at the transmitting field station.

The first "on" code in the secondary indication line circuit in the above description was one 50 during which the secondary indication line circuit was closed because relay PF^2 was picked up during the first "off" period, due to the connection to (+) by way of jumper 282 . Therefore, 55 since the transmission of the first "on" indication is one which requires the closed condition of the secondary indication line circuit, it will be obvious that it was not necessary to precharge the indication circuit, because the message relay 60 MF^1 was supposed to pick up during this "on" period. However in the event that an "on" indication is transmitted which requires that this line circuit be open at the transmitting field station, the application of the charging current 65 to the line circuit just before the message receiving relay is inserted into this line circuit charges the secondary indication line circuit to terminate any flow of current which might be effective to falsely operate the message receiving relay when 70 it is inserted into the circuit and supposed to remain down because of the open condition of the indication circuit.

A similar condition exists during the transmission of "off" indications, for example the sec- 75

ondary indication line circuit is precharged when relay FP^1 is dropped and before relay $2FP^1$ is dropped, over a circuit extending from the (+) terminal of battery IB^1 , charging resistor CRS^1 , back contact 137 of relay FP^1 , front contact 141 of relay $2FP^1$, front contact 149 of relay SA^1 , front contact 153 of relay SB^1 and back contact 159 of relay LV^1 to secondary indication line conductor IL^1 . The dropping of relay $2FP^1$ opens the above described circuit and inserts relay MB^1 in the secondary indication line circuit, but before this relay is included in this circuit the line circuit is precharged for the same purpose previously discussed in connection with the "on" indication condition.

A similar arrangement is provided by contacts 92, 93 and 94 of relays $2FP$ and FP in the control office for precharging the primary indication line circuit by way of charging resistor CRS before the message receiving relays MB and MF are included in this line circuit. Since this arrangement is similar to the arrangement of the contacts of relays FP^1 and $2FP^1$ already described, it is believed unnecessary to point out in detail how this feature operates in connection with the primary indication line circuit. It will be understood that the primary indication line circuit is dependent for its open and closed condition on contacts 177 and 178 of relays PF^1 and PB^1 respectively at the repeater station as selected by contact 225 of relay FP^1 and in the event that the particular one of these contacts involved is open at the time the indication is to be transmitted, then the charging current applied to the primary indication line circuit in the control office is effective to prevent the false picking up of the indication receiving relay when such relay is not to be picked up.

Duplex.—The present invention is applied to a duplex type centralized traffic controlling system as disclosed in the above mentioned prior application 640,062. The operations for separate control and indication cycles have been described and it will now be briefly pointed out how the system operates when controls and indications are transmitted on the same cycle.

The actuation of a starting button in the control office results in the picking up of the associated CD relay during the time that the system is at rest and any time up to the end of the period marked off by the picking up of relay SA in the control office. When a field station initiates the system the relays are conditioned at the field station during the conditioning period, as described in connection with an indication cycle. The control office may pick up a CD relay during this period because the pick-up circuits of the CD relays are controlled through a back contact of the slow acting SA relay in the control office.

After the slow acting SA relay is picked up due to a field station initiating the cycle, then the control office must wait until the next condition of rest of the system before it can pick up a CD relay for the transmission of controls. This means that a CD relay may be picked up at the start of a cycle initiated by a field station any time up to the picking up of relay SA . In this connection however it will be noted that relay C is picked up in the control office by the operation of the starting button so that the picking up of relay FC is ineffective to control relay NC because of open back contact 41 of relay C .

Recalling that a field station can energize its lock out relay any time up to the picking up of its associated FP relay, it will be seen that a field

station may be in condition to transmit its indications during the same cycle that the control office transmits controls because relay CD can be picked up during the initiating period of a cycle initiated from a field station. Similarly, the control office can pick up its CD relay for transmitting controls in the conditioning period of a cycle initiated by a field station. 5

With relay CD picked up and a field station having its lock out relay picked up at the start 10 of a particular cycle, the first impulse of the cycle is (+) or (-) determined as described in Ser. No. 640,062 in connection with a control cycle. This first impulse picks up the SO relays at the proper stations and determines that stepping at 15 these stations will be started. The character of the impulses applied to the control line circuits, as determined by the particular CD relay which is picked up, selects the required station by dropping out the SO relays at the stations not to be 20 selected in the manner described in Ser. No. 640,062. Since a lock out relay, such as relay LO^1 of Fig. 2C or relay LO^2 of Fig. 3, is assumed picked up, stepping will continue at the associated station in the event that it is not the selected 25 station for controls because of the closure of front contact 152 of relay LO^1 or a similar contact operated by relay LO^2 but not shown.

The resulting cycle of operations is thus the same, in so far as the transmission of impulses 30 over the control line circuits for the selection of a station is concerned, as was previously described in connection with a control cycle alone. Similarly the resulting operations of the cycle, in so far as the conditioning of the indication line circuits is concerned, is the same as described for a cycle during which indications alone were transmitted. Since transmission over the control and indication line circuits is effected during a duplex cycle by separate and distinct circuit instruments 35 it is obvious that these transmissions may be combined and brought about during a single cycle of operations, conveniently referred to as a duplex cycle.

Having thus described one specific embodiment 45 of a centralized traffic controlling system it is desired to be understood that the particular arrangement illustrated is merely typical of applicant's invention and is not intended to show the exact circuit design necessary to carry out 50 the features of the invention, but has been selected to facilitate in the disclosure rather than to limit the scope of the invention and it is further to be understood that various modifications 55 may be made and various adaptations and alterations may be applied to the specific form disclosed in order to meet the various problems encountered in practice and that the system may be varied in the number of repeater and field stations, the amount of apparatus installed at the 60 particular repeater and field stations and the number of steps provided for station selection, station registration and control and indication codes transmitted, all without in any manner departing from the spirit or scope of the invention 65 except as limited by the appended claims.

What I claim is:—

1. In a remote control system, a control office, a first station and a second station, a primary line circuit connecting said office with said first station, a secondary line circuit connecting said first station with said second station, stepping mechanisms at said office and at said stations, means for operating all said mechanisms in synchronization through a plurality of cycles, means at 75

said second station controlled by said mechanism at that station for applying a first series of impulses to said secondary line circuit during a first one of said cycles to form a code, means at said 5 first station rendered effective by said mechanism at that station for receiving and storing said first series of impulses during said first cycle, means at said first station including said storing means and said mechanism at that station for 10 applying a second series of impulses corresponding to said first series to said primary line circuit during a second one of said cycles to form a duplicate of said code, and means at said control office controlled by said mechanism at the 15 office and responsive to said second series of impulses, whereby distinctive messages are conveyed to said office from said second station.

2. In a remote control system, a control office, a first station and a second station, a primary line circuit connecting said office with said first station, a secondary line circuit connecting said first station with said second station, stepping mechanisms at said office and at said stations, means for operating all said mechanisms step-by-step in synchronism through a cycle of operation when initiated, means at said second station for initiating a first cycle of operation, means at said second station controlled by said mechanism at that station for applying a first series of impulses to said secondary line circuit during said first cycle, means at said first station rendered effective by said mechanism at that station for receiving and storing said first series of impulses during said first cycle, initiating means at said 30 first station responsive to the operation of the stepping mechanism at said first station during said first cycle for initiating a second cycle, and transmitting means controlled by said mechanism at said first station in accordance with said storing means at that station for applying a second series of impulses to said primary line circuit during said second cycle.

3. In a remote control system, a plurality of locations including a control office and a plurality of field stations, a primary control line circuit and a primary indication line circuit connecting said office with a first one of said stations, a secondary control line circuit and a secondary indication line circuit connecting said first station with a second one of said stations, means in said control office for controlling the application of series of time spaced control impulses to said primary control line circuit, means at said first station responsive to said control impulses on said primary control line circuit for directly repeating similar time spaced control impulses into said second control line circuit, two code transmitting means at each of said stations for transmitting messages over said indication line circuits, means rendering one of said code transmitting means at said second one of said stations effective during each impulse of a first series on said secondary control line circuit, means rendering the other of said code transmitting means at said second station effective during each time space of said first series of impulses on said secondary control line circuit, means for receiving and storing at said first one of said stations messages transmitted during said first series of impulses, and means governed by the stored messages and including the code transmitting means at said first station for transmitting the stored messages over said primary indication line circuit to said office during a second series of impulses on said control line circuits.

4. In a remote control system, a control office and a plurality of field stations including a repeater station, a first control line circuit and a second control line circuit each interconnecting its respective group of said plurality of field stations with said repeater station, impulsive means in said office for applying a series of characteristic control impulses to said first control line circuit, impulsive means at said repeater station for receiving each of said control impulses and retransmitting a fac-simile thereof to said second control line circuit immediately upon the receipt thereof, a first indication line circuit and a second indication line circuit each interconnecting its respective group of said plurality of field stations with said repeater station, automatically controllable contacts at said plurality of said stations, transmitting means at each of said stations associated with said second indication line circuit for applying a series of indication impulses to said second indication line circuit to conform with a distinctive code call corresponding to the station transmitting and the positions of said contacts at that station, receiving and storage means at said repeater station for receiving and storing said series of indication impulses on said second indication line circuit, means for retransmitting a fac-simile of said stored indication impulses to said control office over said first indication line circuit only after said series of indication impulses on said second indication line circuit has been completely received and stored, and means at said control office controlled by the fac-simile of said indication impulses on said first indication line circuit, whereby said distinctive code call and the positions of said contacts are registered in said control office.

5. In a remote control system, a control office, a first station and a second station, a primary line circuit connecting the control office with said first station, a secondary line circuit connecting said first station and said second station, code transmitting means at said first station operable through cycles of operation to impress series of code impulses on said primary line circuit, code transmitting means at said second station operable through cycles of operation to impress series of code impulses on said secondary line circuit, code receiving means at said control office and at said first station each operable through cycles of operation, means for operating said code transmitting means at said second station and said code receiving means at said first station in synchronism through a first cycle of operation, code storing means at said first station controlled by said code receiving means at that station for storing the code received during said first cycle of operation, means for operating said code transmitting means at said first station and said code receiving means at said control office in synchronism through a second cycle of operation, said code transmitting means at said first field station being governed by said code storing means at that station in accordance with the code stored during said first cycle of operation, and means preventing the operation of said code transmitting means at said second station through another cycle of operation until after said code transmitting means at said first station has operated through its cycle of operation to transmit the code stored in said code storing means at that station during said first cycle of operation.

6. In a remote control system, a control office, first and second stations, a stepping line circuit

connecting said control office with said stations and having series of impulses impressed thereon to comprise cycles of operation, a primary line circuit connecting the control office with said first station, a secondary line circuit connecting said first station with said second station, code transmitting means at said first station operable by a series of impulses on said stepping line circuit through a cycle of operation to impress a series 5 of code impulses on said primary line circuit, code transmitting means at said second station operable by a series of impulses on said stepping line circuit through a cycle of operation to impress a series 10 of code impulses on said secondary line circuit, code receiving means at said control office and at said first station each operable through cycles of operation by impulses on said stepping line circuit, means for setting said code transmitting means at said second station and said 15 code receiving means at said first station into operation for a cycle of operation, said means being effective only when said secondary line circuit is closed at said first station, code storing means at said first station controlled by said code 20 receiving means at that station for storing the code received during the first cycle of operation over said secondary line circuit, means opening said secondary line circuit at said first station whenever there is a code stored in said code 25 storing means, and means for setting said code transmitting means at said first station and said code receiving means at said control office into a cycle 30 of operation when there is a code stored in said code storing means, said code transmitting means 35 being governed for such cycle of operation by said storing means in accordance with the code stored therein.

7. In a remote control system, a control office, first and second stations, a repeater station between said first and said second stations, a stepping line circuit connecting said control office with said stations and having series of impulses impressed thereon to comprise cycles of operation, a primary indication line circuit connecting the control office with said first station and said repeater station, a secondary indication line circuit connecting said repeater station with said second station, code transmitting means at said first and said repeater stations operable by series of impulses on said stepping line circuit through cycles of operation to impress series of code impulses on said primary indication line circuit, code transmitting means at said second station operable by a series of impulses on said stepping line 55 circuit through a cycle of operation to impress a series of code impulses on said secondary indication line circuit, code receiving means at said control office and at said repeater station each operable through cycles of operation by impulses 60 on said stepping line circuit, means for setting said code transmitting means at said second station and said code receiving means at said repeater station into operation for a cycle of operation, said means being effective only when said 65 secondary line circuit is closed at said repeater station, code storing means at said repeater station controlled by said code receiving means at that station for storing the code received during a preceding cycle of operation over said secondary 70 indication line circuit, means opening said secondary indication line circuit at said repeater station whenever there is a code stored in said code storing means, means for setting said code transmitting means at said first station and said code 75 receiving means at said control office into a cycle

of operation, means for setting said code transmitting means at said repeater station and said code receiving means at said control office into a cycle of operation when there is a code stored in said code storing means at said repeater station, said code transmitting means being governed for such cycle of operation by said storing means in accordance with a code stored therein, and means controlled through the medium of said primary indication line circuit for allowing said 10 first station and said repeater station to transmit only on successive cycles of operation in that order when both stations are ready to transmit at the same time. 5

8. In a remote control system; a first control line circuit connecting a control office with a repeater station; a second control line circuit connecting said repeater station with a field station; a first indication line circuit connecting said control office with said repeater station; a second indication line circuit connecting said repeater station with said field station; means at said office for applying different series of distinctive time space impulses to said first control line circuit for the transmission of controls thereover; 15 means at said repeater station responsive to impulses in said first control line circuit for contemporaneously applying duplicate impulses to said second control line circuit; stepping mechanisms at said office and said stations, each operable step-by-step through a cycle of operation in response to a series of impulses on said control line circuits; means at said field station responsive on each step of its stepping mechanism to the distinctive character of impulse on said 20 second control line circuit for that step, whereby the control messages are received at the field station; means at said field station effective on each step of its stepping mechanism during a first cycle of operation to distinctively condition said second indication line circuit for transmitting indication messages to said repeater station; storing means at said repeater station responsive on each step of its stepping mechanism during said first 25 cycle of operation to the distinctive conditions 30 of said second indication line circuit for that step for storing the indication messages transmitted from said field station; transmitting means at said repeater station rendered effective on each step of a second cycle of operation of 35 its stepping mechanism to distinctively condition said first indication line circuit in accordance with the distinctive conditions stored by said storing means; and means at said control office responsive on each step of said second cycle of 40 operation of its stepping mechanism to the distinctive condition of said first indication line circuit for that step, whereby the indication messages transmitted from said field station during said first cycle of operation are received during 45 said second cycle of operation. 40

9. In a remote control system; a first stepping line circuit connecting a control office with a repeater station; a second stepping line circuit connecting said repeater station with a field station; a first indication line circuit connecting said control office with said repeater station; a second indication line circuit connecting said repeater station with said field station; means at 55 said office for applying series of time spaced impulses to said first stepping line circuit; means at said repeater station responsive to impulses in said first stepping line circuit for contemporaneously applying impulses to said second stepping line circuit; line relays included in said first 60

stepping line circuit at said control office and at said repeater station; line relays included in said second stepping line circuit at said repeater station and at said field station; stepping mechanisms at said office and said stations; means at said control office and at said field station for operating the respective step-by-step mechanisms through a cycle of operation in response to a series of impulses as repeated by the respective line relays at such locations; means at said field station effective on each step of its stepping mechanism during a first cycle of operation to distinctively condition said second indication line circuit for transmitting indication messages to said repeater station; storing means at said repeater station responsive on each step of its said stepping mechanism during said first cycle of its operation to the distinctive conditions of said second indication line circuit for storing the indication line messages transmitted from said field station; transmitting means at said repeater station rendered effective during a second cycle of operation of its stepping mechanism to distinctively condition said first indication line circuit on each step in accordance with said distinctive conditions stored by said storing means; means at said control office responsive on each step of said second cycle of operation of its stepping mechanism to the distinctive condition of said first indication line circuit for that step; whereby the indication messages transmitted from said field station during said first cycle of operation are received during said second cycle of operation; means at said repeater station for causing its stepping mechanism to operate through a first cycle of operation in response to impulses repeated by its said line relay in said second stepping line circuit and to operate through said second cycle of operation in response to impulses repeated by its said line relay in said first stepping line circuit.

10. In a remote control system; a control office; a first group of field stations including a repeater station; a second group of field stations; a primary line circuit connecting said office with said first group of field stations; a secondary line circuit connecting said repeater station with said second group of field stations; a stepping mechanism at said office and at each of said stations; means for operating said control office mechanism step-by-step through a cycle of operation in synchronism with said station mechanisms when initiated into operation, but only those station mechanisms which are rendered effective at such stations being capable of operation throughout a complete cycle of operation; means at each station of said second group of stations for initiating a first cycle of operation and rendering its mechanisms effective; means at each station of said second group controlled by said mechanism at that station for applying a first series of coded impulses to said secondary line circuit during a first cycle when such first cycle has been initiated at that station; means at said repeater station for initiating its said mechanism and rendering it effective at that station for said first cycle; receiving and storing means at said repeater station controlled by said mechanisms for storing said first series of coded impulses on said secondary line circuit during said first cycle; initiating means at said repeater station responsive to the completed operation of the stepping mechanism at said repeater station during said first cycle for initiating a second cycle of operation and rendering its said mechanism effective; transmitting means controlled by said mechanism at said repeater station and operated in accordance with said storing means at that station for applying a second series of coded impulses to said primary line circuit during said second cycle of operation, said second series of coded impulses corresponding to said first series of coded impulses; and code receiving means at said control office controlled by its stepping mechanism and responsive to said coded impulses in said primary line circuit.

WILLIAM D. HAILES.
